UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

OIL HEATING STOVE.

1,404,006.

Specification of Letters Patent. Patented Jan. 17, 1922.

Application filed August 15, 1921. Serial No. 492,318.

To all whom it may concern:

Be it known that I, ATWELL J. BLACKFORD, a citizen of the United States, residing at Cleveland, in the county of Cuyahoga and State of Ohio, have invented certain new and useful Improvements in Oil Heating Stoves, of which the following is a specification, reference being had therein to the accompanying drawing.

10 This invention relates to improvements in oil heating stoves, of that type in which the burner is surmounted by a swinging heating drum extending upward therefrom.

In this type of stove, the heating drum 15 carries an air controlling cone, which surrounds the outer wick tube, the upper end of the wick, the lower part of the flame and a part of the spreader. It is necessary that this cone be evenly positioned in respect to the upper end of the wick, the flame and the spreader in order to produce an even flame. If this air-controlling cone is nearer to one 20 side of the wick and the flame produced thereby, one side of the flame will burn a higher and smoky flame, because of imperfect air distribution and an improper combustion.

Heretofore, this air-controlling cone has been rigidly attached to the heating drum 25 and it is difficult to insure the proper seating of this air-controlling cone, and it has required separate careful adjustment of each drum and cone, which adds to the expense of manufacture, and in transportation the hinge of the drum, or some other part, is frequently distorted sufficiently to cause the imperfect positioning and seating of the air-controlling cone.

The object of my invention is to provide a 30 construction whereby the air-controlling cone is always automatically properly seated and properly positioned without the necessity of prior adjustment and which will not be affected by distortions which happen in 45 transportation or use.

I accomplish this result by so constructing the parts that the air-controlling cone "floats" within the lower end of the heating drum with sufficient movement independent 50 of the drum to permit it to automatically properly position and seat itself when the drum is turned over the burner.

The accompanying drawing is a vertical section, showing my improved construction.

55 Referring now to the drawing in which

similar reference characters designate the same parts, 1 is the fount or reservoir carrying the usual wick tubes 2, in which the wick 3 is located in the usual manner. The wick tube and wick are of the annular or Argand type and is surmounted by the usual form of perforated spreader 4. A perforated upwardly extending annular flange 5 is provided, which extends from the reservoir 1 and surrounds the lower portion of the wick 60 tubes. This is called in the art a perforated fount head. The reservoir, with the construction just described, is seated in a supported perforated housing 6, which is supported by suitable legs 7.

A heating drum 8 surmounts the burner construction and the housing 6, the heating drum 8 being hinged to the housing 6 at 9, so that it may be turned back to expose the wick to be lighted in a manner well understood by those skilled in this art.

The drum 8 carries at its lower end an inwardly and downwardly inclined flange 10, which is referred to in this art as the lower drum ring.

The air-controlling cone 11 is carried by the drum 8, so that when it is moved back for lighting purposes, the cone is carried with it. This cone 11 surrounds the upper end of the wick tube, the upper end of the 85 wick 3, and a part of the spreader 4. The function of this cone 11 is to properly provide and direct the air to the upper end of the wick and the flame issuing therefrom. This member 11 is necessary to produce a 90 large flame without smoking and it is necessary that this cone be positioned so that it is substantially equi-distant from all parts of the upper end of the wick and the flame issuing therefrom. That is to say, the cone 95 11 must be so positioned that the wick is substantially in the center thereof, and it is also necessary that the lower end 12 of the cone be properly seated on the upper end of the perforated reservoir head 5. If this 100 cone is not properly seated on the perforated reservoir head 5, or if it is not properly positioned so that the upper end of the wick and the flame therefrom are substantially in the center of the cone 11, the flame will 105 be uneven and burning higher in places, cause a smoky flame.

Heretofore, this air-controlling cone 11 has been rigidly attached to the drum ring 10 and difficulty has been experienced in 110

causing the cone to properly seat on the reservoir 5, and properly positioned in respect to the upper end of the wick and the flame. As a consequence each stove has to be manufactured and adjusted so far as its hinged connection and its cone 11 and ring 10 are concerned, which has added to the cost of manufacture. Again it has been found that after they are properly positioned, the hinge or other parts frequently become distorted in transportation by rough handling so that the cone 11 does not properly seat and properly position. Again, the hinge becomes distorted in use by careless handling with the drum hinged backward or otherwise, thus causing the cone to be improperly seated and improperly positioned with the result of uneven smoky flame.

By my improvement, I accomplish the automatic and certain properly seating and positioning of the cone when the heating drum is in position over the burner. I accomplish this by making the cone 11 a floating member. This is done by making the cone 11 separate from the drum ring 10 and making it loose in the drum ring, so that the cone 11 has lateral and vertical movement independent of the drum ring 10 and drum 8. The diameter of the upper portion of the cone is made sufficiently smaller than the diameter of the opening 13 in the drum ring to permit the cone to have lateral and vertical movement independent of the ring. The lower end 14 of the cone 11 is enlarged 35 outward so that it automatically properly positions itself on the upper end of the reservoir head 5, and when properly positioned on the head 5, it is necessarily properly positioned in respect to the upper end 40 of the wick, its flame and the spreader.

I further provide the upper end of the cone 11 with an outwardly enlarged and upwardly extending air deflector 15, which serves to direct outward the air which passes between the cone 11 and the drum ring 10, through the surrounding space f.

From the foregoing description, it will be readily seen that when the drum is hinged backward, the cone 11 is carried with it and that after the wick is lighted and the heating drum 8 is turned back to operative position over the burner, the cone 11 automatically and certainly properly seats itself on the reservoir head 5, and to be properly seated there is necessarily properly positioned in respect to the upper end of the wick, its flame and the spreader 4. It will be further understood that this construction overcomes the necessity in manufacture of fitting and adjusting the drum, its hinge and the cone so that the cone properly seats and positions itself. It will also be further understood that the properly seating and positioning of this floating cone 11 is not 60 affected by distortions of the drum, its

hinge or other parts, such as would occur in transportation or in use.

By this arrangement I have overcome one of the most troublesome features of burners of this type, which has caused them to become unsatisfactory in use, as well as to reduce the cost of manufacture.

From the foregoing description, it will be seen that the reservoir head 5 co-acts with the lower end of the cone 11, to properly position it, and it is a positioning member for the floating cone.

I do not limit myself to the precise construction herein shown and described, for this may be varied so long as it is within the scope and spirit of the appended claims.

Having thus described my invention, what I claim and desire to secure by Letters Patent is:-

1. A heater of the type described, comprising a burner, a drum surmounting the burner, an air-controlling member having vertical and lateral movement independent of the drum, and a member independent of the drum and co-acting with the lower end of the cone to properly seat and position the cone.

2. A heater of the type described, comprising a burner, a movable drum surmounting the burner, an air-controlling member between the drum and the burner, the member having movements independent of the drum, and a positioning member co-acting with the lower end of the cone, for the purpose described.

3. A heater of the type described, comprising a burner, a movable drum surmounting the burner, an air-controlling member between the drum and the burner and surrounding the upper end of the wick, and a positioning member independent of the movement of the drum and co-acting with the air-controlling member for positioning it in respect to the burner.

4. A heater of the type described, comprising a burner, a movable drum seated thereabove, an annular air-controlling member surrounding the upper end of the burner and a positioning member connected with the burner and co-acting with the air-controlling member for properly seating and positioning the latter.

5. A heater of the type described, comprising a burner, a movable drum surmounting the burner, an annular air-controlling member movable with the drum and having a movement independent thereof for the purpose described, and a flange extending upwardly and connected with the burner, the lower end of the air-controlling member extended outward to automatically seat and position itself when the drum is in operative position.

6. A heater of the type described, comprising a burner, a movable drum surmounting

the burner, a flange extending upward around the burner, and an annular air-controlling member movable with the drum and having lateral and vertical movements independent of the drum, the lower end of the air-controlling member constructed to automatically interlock with the flange for properly seating and positioning itself independent of the drum.

10 7. A heater of the type described, comprising a burner, a drum surmounting the burner, an upwardly extending flange surrounding the burner, the lower end of the drum having an inwardly extending flange 15 with a central opening, and an annular air controlling member passing through the said drum flange opening and having lateral and vertical movements therein, the lower end of the air-controlling member and the upper 20 end of the flange constructed to automatically interlock, for the purpose described.

8. A heater of the type described, comprising a burner, an annular air-controlling member to surround the upper end of the burner, a drum movable in respect to the burner, the air-controlling member movable with the drum but having vertical and lateral movements independent of the drum, and means for automatically seating the air 30 controlling member independent of the drum, the upper end of the air-controlling

member having an outwardly and upwardly extending air-deflector.

9. A heater of the type described, comprising a burner, a movable drum surmounting the burner, an annular air-controlling member surrounding the upper end of the burner movable with the drum, and means independent of the drum co-acting with and automatically positioning the air controller 40 when the drum is moved to operative position.

10. A heater of the type described, comprising a burner, a movable drum surmounting the burner, an air-controlling cone surrounding the upper end of the burner and movable with the drum but having vertical and lateral movement independent of the drum, and means independent of the drum and co-acting with the cone and automatically 45 positioning it when the drum is moved to operative position.

11. A heater of the type described, comprising a burner, a drum surmounting the burner, an air-controlling cone floatingly 55 supported by the drum when out of operative position, and means for automatically positioning the cone when the drum is moved to operative position.

In testimony whereof I hereunto affix my 60 signature.

ATWELL J. BLACKFORD.
